UNITED STATES PATENT OFFICE.

FRANK E. PFEIFFER, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed March 12, 1923. Serial No. 624,398.

My invention relates to autographic registers.

It is an object of my invention to provide a small, light, simple switch and portable autographic register economical to manufacture and simply adjusted as well as operated.

It is an additional object to provide a case which will provide ready access to the interior of the register to facilitate the adjustment of the several parts.

It is an additional object in this form of a register to provide a simple and effective carbon roll and means of retaining the carbon in position.

It is a further object to provide in combination with these parts a handle and handle stop to effectively hold the paper sheets in position during the tearing off process and during the writing period.

Referring to the drawings:

Fig. 1 is a section taken on the line 1—1 of Fig. 6;

Fig. 2 is a plan view of the paper roll units in their supporting frames;

Fig. 3 is an end elevation of the complete machine looking at it from the ejecting end showing the ejecting end of the cover opening and the top cover in elevated position;

Fig. 4 is a section showing the details of one of the anti-weave rollers;

Fig. 5 is a side elevation of the complete machine showing the handle and handle stop;

Fig. 6 is a rear elevation of the register with the rear wall open;

Fig. 7 is a side elevation of the register with the carbon roll cover open and the top cover up;

Fig. 8 is a detail view partially in section on the line 8—8 of Fig. 7 looking in the direction of the arrow showing the carbon roll support.

Referring to the drawings in detail, 1 is the bottom of the register resting upon the supports 2 protecting the supporting table and the like from injury.

At the forward end of the register there is a hinge door mounted upon the supporting member 3, carried by the side wall 4. The hinge member 5 turns on 3 and is connected to the end wall which extends upwardly and is turned over at a right angle as at 8 to overlap the projecting end of 9 of the cover 10.

The cover 10 is pivoted at 11 in a similar manner upon the side wall 4.

It will be understood that the end wall 6, the cover 10 and the rear wall 12 are not only pivoted on the side wall 4 but on the 60 companion side wall 13. The end wall 12 is pivoted at 14 which is carried by the side walls 4 and 13. The front or forward wall 6 is held in position when closed by a lock shown in a plan view in its unlocked position in Fig. 6.

The locking is effected by transversely moving members carried on the end wall 6. These members are respectively designated 15 and 16 and have handles 17 and 18 which enable the operator to clamp the handles between the thumb and forefinger thereby moving 15 and 16 together and disengaging their heads 19 and 20 from engagement with the lugs 21 and 22 carried by the side walls 75 respectively thus unlocking the front end wall. Resisting this movement and serving to maintain 19 and 20 in engagement with 21 and 22 is a coil spring 23 secured between the inner ends of 15 and 16. 15 and 16 are 80 guided in their transverse movement by the guide pins 24 which are fastened in the guide bases 25.

A similar lock is provided for the other end wall 12. These end walls serve to maintain the supply paper roll rack 26 and record roll rack 27 in their position in the register.

These racks are supported in the guide way formed by the members 28 and 29 carried by the side wall so after the rolls have 90 been installed in the racks, they may be positioned in the register on these racks or guide ways 28 and 29. The rack 26 consists of a U-shaped member with a brace 30 therebetween. It may be adapted to carry any 95 number of rolls but in this case I have shown the two rolls. Rolls 31 and 36 are each provided with an axle 32 which rests in a support 33 having a broad flat bearing portion to maintain the roll in position and prevent 100 lateral movement. The other end of the axle 32 rests in a bearing member 34 close to the adjacent side member of the rack. This end of the axle has a bearing plate 35 to assist in maintaining the paper in proper position 105 on the axle 32.

The paper rolls 31 and 36 have the paper unwound from them and conveyed over the guide rollers 37 and 38 respectively, over the top of the writing table 39 which is pivotally 110

supported on 40. 40 is carried by the walls 4 and 13.

These paper sheets pass over 39 and pass beneath the cover 10 in which there is provided an opening 41. The carbon sheet 42 is interleaved between the paper sheets 31^a and 36^a in order that there may be a record made upon 31^a which is conveyed between the rollers 43 and 43^a around the tension rods 44 10 and 45, and over the anti-weave rollers 46 to the record roll 47.

The record roll 47 is carried in the rack 27 by its axle 48. Upon this roll is mounted a gear 49. The gear is frictionally engaged 15 with the record roll 47 by means of friction plates 49^a on either side thereof, and the metallic plates 49^b, one of these plates being between the hub portion of the shaft and the record roll proper. This frictional engagement 20 allows the record roll to be maintained stationary at times, while the gear is given motion through operation of the operating handle, etc., of the register. The gear 49 meshes with the intermediate gear 50 which 25 is fixed to the shaft 51. This gear 50 engages with a gear 53 which is mounted upon the shaft 54 journaled in the side walls 4 and 13. 54 carries the roller 43^a which has a series of fine grooves 55 cut therein so that 30 the sharp edges between the grooves will engage with the paper. The companion roller 43 has similar grooves 55 cut in it. This roller 43 has a gear 56 which meshes with a gear 57 on the shaft 54. The gear 57 in 35 turn meshes with the master driving gear 58 mounted on the driving shaft 59 which carries the handle 52. This handle 52 at 61 engages with the upper end of the stop 62. 62 is pivoted on the supporting member 40 63 which in turn is mounted upon the side wall 4. A finger piece 64 and a stop 65 are provided on the stop 62. A lug 66 is mounted on the side wall 4 to engage with the stop 65.

The roller 43 has a housing 67 carried by 45 the cover 10. At the forward lower end of this housing which is above 9 and 8 is an opening 68 through which a portion of the sheet 36^a is ejected.

The sheet 31^a as hereinbefore described 50 is passed over the tension rods 44 and 45 for the purpose of putting it under tension so that it will bear down upon the anti-weave rollers shown in detail in Fig. 4, and arranged in series spaced from one to another as shown in Fig. 3. The sleeves 69 which space the anti-weave roller 46 from the side walls and from one another are mounted upon a supporting rod 70. Both 55 69 and 46 may turn freely on 70. 46 is provided with tapered portions 71 and 72 meeting at 73 to form a ridge for engagement with the paper to prevent the lateral movement or the weave of the paper to insure its exact alignment and perfect winding upon the record roll 47. Referring to

the carbon roll container, a cup 74 is pivoted at 75 to the side wall 13 and the carbon roller is held in its closed position by the insertion of the pins 76 in the apertures 77 in the cup. The pins 76 are carried by the cover 10 and the apertures in the cup 74 at the top thereof are directly beneath the pins 76 so that as they descend with the cover 10 the carbon roll is held in position.

When the carbon roller is in its open position as shown in Fig. 3 the carbon roll axle 78 is adapted to swing outwardly upon the support 79 which is mounted upon the side wall 13. The axle 78 is retained in 79 by the pin 80. The axle 78 is disposed at an acute angle to the support 79 so that the axle 78 will swing in a plane at an acute angle to the horizontal and above the horizontal so that it is easy for the operator to slip the carbon roll 81 upon the axle 78 against the pressure washer 82. This pressure washer 80 engages with a coil spring 83, the other end of which engages with a stationary washer 84. It will be understood that the spring 83 surrounds the axle 78 and it will be 85 further understood that the washer 82 is adapted to move freely upon the axle 78. In the closed position of the axle 78, as shown in Fig. 7, the end of the carbon roll 81 opposite to that in contact with the washer 82 abuts against the supporting lug 85 carried by the side wall 13 which also serves as a support for the axle 78. The carbon roll is yieldingly engaged due to the act of the spring 83 between the washers 82 90 and 85 the lug thus preventing the carbon roll from unwinding when in its closed position save when positively actuated as when the operator draws it across the writing table to expose a fresh surface.

In order to hold a carbon sheet in position on the writing table the outer free end of the carbon sheet on the side of the table opposite to the carbon roll is clamped by the extension portion of the cover 10 and a 110 clamping member 86 carried thereby at right angles thereto which clamps the sheet against the side wall 4 pressing the carbon sheet between the clamp 86 and the side wall 4. The sheet is also securely pressed 115 between the cover 10, the writing table 39 and the upper edge of the side wall 4. It will be understood that the cover 10, due to the overlapping of 8 upon 9 and the locking of the end wall 6, will prevent any movement of the carbon. The side walls 13 and 4 are provided with upwardly projecting portions 87 with slots 88 cut therein in which the reduced ends of 89 are allowed to freely travel, 89 being the support for the roller 43. 120

As heretofore stated, in machines of this character the paper on its way to the record roll to be rewound will tend to move to one side or the other and be difficult to wind. It has been found in practice that rollers 46 125

of the shape shown and described overcome this tendency of the paper to move or weave from side to side and present the paper to the record roll in proper alignment. The 5 term anti-weaving roller, as used in the specification and claims, is therefore to be understood as meaning a roller to prevent the moving of the paper from one side to the other in its travel to the record roll.

10 It will be understood that I do not desire to be confined to this specific adaptation of my invention, but comprehend within it suitable modifications which may be necessary in adapting it to varying conditions.

15 Having thus fully described my invention, what I claim as new and desire to secure by Letters Patent, is:—

1. In an autographic register having end walls, side walls, a writing table, and a cover, means pivotally mounting the cover on 20 the side walls, supporting means on one of the side walls for supporting a roll of carbon, clamping means carried by this cover adapted to clamp the free end of the carbon 25 sheet between it and a portion of the side walls, a cover for the carbon roll pivotally mounted on the side of the register having apertures in the upper portion thereof adapted to engage with pins downwardly 30 disposed on the bottom of the cover whereby when the cover is closed the pins will engage with the aperture and will hold the carbon roll cover in position.

2. In an autographic register having end 35 walls, side walls, a writing table, and a cover, means pivotally mounting the cover on the side walls, supporting means on one of the side walls for supporting a roll of carbon, clamping means carried by this 40 cover adapted to clamp the free end of the carbon sheet between it and a portion of the side walls, a cover for the carbon roll pivotally mounted on the side of the register having apertures in the upper portion 45 thereof adapted to engage with pins downwardly disposed on the bottom of the cover whereby when the cover is closed the pins will engage with the aperture and will hold the carbon roll cover in position, said carbon 50 roll support consisting of an axle pivotally mounted upon one side wall of the register within the carbon roll cover, said pivotal connection being at an angle to the horizontal.

55 3. In an autographic register having end walls, side walls, a writing table, and a cover, means pivotally mounting the cover on one of the side walls, supporting means on one of the side walls for supporting a roll of carbon, clamping means carried by this 60 cover adapted to clamp the free end of the carbon sheet between it and a portion of the side walls, a cover for the carbon roll pivotally mounted on the side of the register

having apertures in the upper portion 65 thereof adapted to engage with pins downwardly disposed on the bottom of the cover whereby when the cover is closed the pins will engage with the aperture and will hold the carbon roll cover in position, said carbon 70 roll support consisting of an axle pivotally mounted upon one side wall of the register within the carbon roll cover, said pivotal connection being at an angle to the horizontal, and yielding means to prevent said 75 carbon roll from unwinding save from a predetermined pull exerted by the operator.

4. In an autographic register, a carbon 80 roll support consisting of a lug mounted upon one wall of the register, an axle pivotally mounted thereon for supporting the carbon roll, said pivotal connection being so arranged that the axle will swing in a plane at an angle to the horizontal.

5. In an autographic register, a carbon 85 roll support consisting of a lug mounted upon one wall of the register, an axle pivotally mounted thereon for supporting the carbon roll, said pivotal connection being so arranged that the axle will swing in a plane 90 at an angle to the horizontal, a support for the free end of the axle carried by the wall of the register and also adapted to engage one end of the carbon roll supported on the axle and yielding means on the other end of the axle for engaging with the other end of the roll for forcing the roll against 95 second support.

6. In an autographic register, a carbon 100 roll support consisting of a lug mounted upon one wall of the register, an axle pivotally mounted thereon for supporting the carbon roll, said pivotal connection being so arranged that the axle will swing in a plane 105 at an angle to the horizontal, a pivotal cover for the carbon roll and its support pivoted at the bottom of a cover adapted to swing outwardly and downwardly to permit of the free lateral movement of the carbon roll.

7. In an autographic register, a carbon 110 roll support consisting of a lug mounted upon one wall of the register, an axle pivotally mounted thereon for supporting the carbon roll, said pivotal connection being so arranged that the axle will swing in a plane 115 at an angle to the horizontal, a support for the free end of the axle carried by the wall of the register and also adapted to engage one end of the carbon roll supported on the axle and yielding means on the other end 120 of the axle for engaging with the other end of the roll for forcing the roll against second support, and means carried by the register cover for engaging with the carbon roll cover in its closed position for maintaining 125 it in that position.

In testimony whereof, I affix my signature.
FRANK E. PFEIFFER.
